BOTTLE CARRYING CASE

Kenneth K. Hudson, Tampa, Fla.

Application January 2, 1953, Serial No. 22,995

Term of patent 14 years

(Cl. D58—4)

To all whom it may concern:

Be it known that I, Kenneth K. Hudson, a citizen of the United States, residing at Tampa, State of Florida, have invented a new, original, and ornamental Design for a Bottle Carrying Case, of which the following is a specification, reference being had to the accompanying drawing, forming a part hereof.

Fig. 1 is a top plan view of a bottle carrying case, showing my new design.

Fig. 2 is an end elevation thereof.

Fig. 3 is a side elevation thereof.

Fig. 4 is a bottom view thereof.

Fig. 5 is a sectional view thereof, taken along the line 5—5 of Fig. 1.

I claim:

The ornamental design for a bottle carrying case, as shown.

KENNETH K. HUDSON.
